ATTORNEY

UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC-FURNACE RESISTOR.

Application filed June 3, 1921. Serial No. 474,744.

To all whom it may concern:

Be it known that I, ORA A. COLBY, a citizen of the United States, and a resident of Irwin, in the county of Westmoreland and 5 State of Pennsylvania, have invented a new and useful Improvement in Electric-Furnace Resistors, of which the following is a specification.

My invention relates to electric furnaces 10 and particularly to electric-resistance furnaces and it has for its object to provide a relatively simple and inexpensive combination granular and solid resistor for such furnaces.

15 In co-pending application, Serial No. 454,776, filed March 23, 1921, Patent Number 1,443,580 by G. M. Little and assigned to the Westinghouse Electric & Manufacturing Company, there is disclosed an electric-resistance furnace in which the resistor comprises a plurality of relatively thin flat carbonaceous plates, the flat surfaces being pressed together by suitable resilient means. The resistance of such a resistor is relatively 20 low and a relatively large current is required to produce the temperature desired 25 in the furnace chamber.

My present invention discloses a combined resistor comprising a plurality of 30 dished carbonaceous members in which granular-electric conducting material may be placed, the dished members being of such form as to permit of compressing the granular material in the dished members and 35 simultaneously interlocking them.

In the single sheet of drawings:

Figure 1 is a view, in vertical cross-section, of an electric-resistance furnace comprising the device embodying my invention; 40 Fig. 2 is a view, in vertical cross-section, of a portion of the device embodying my invention, and

Fig. 3 is a view, in side elevation, of one of the dished members illustrated in Fig. 2.

45 An electric-resistance furnace 10 comprises an outer metallic casing or framework 11 provided with suitable supporting members 12. Outer walls 13 comprise a plurality of bricks or blocks of heat-insulating material located in the casing 11. Inner walls 14 comprise a plurality of bricks or blocks of any suitable high-temperature-resisting material, the walls 14 being suitably spaced apart to form a furnace chamber 15

of any suitable or desired contour and dimensions. 55

A heating element, located in the chamber 15, comprises a plurality of dished elements 16 to be described hereinafter more in detail. A graphite terminal block 17 is provided at 60 one end of the built-up heating element the outer surface of which is operatively engaged by an elongated carbonaceous electrode 18 extending through the furnace walls 13 and 14. 65

The outer end of the electrode 18 has mounted thereon a metallic contact terminal 19 to which the supply-circuit conductors (not shown) may be connected.

A resilient compressing means for the 70 built-up heating element comprises a suitably mounted adjusting screw 20, engaging the outer end of a helical spring 21, the inner end of which engages the outer surface of the contact terminal 19, an insulating 75 member 22 being placed between the spring and the terminal to suitably insulate them from each other. It is to be understood that the compressing means illustrated in Figure 1 is schematic only and that any suitable or desired compressing means may be employed. 80

In order to suitably insulate the contact terminal 19 from the metallic framework 11, a member 23 of asbestos may be placed in the 85 outer wall 13 and the casing 11, surrounding the contact terminal 19 to effectively insulate the terminal from the casing.

As the temperature of the electrode 18 is relatively very high at that part located at 90 about the middle of the two walls 13 and 14, it is desirable that some means be provided to protect the electrode against oxidizing air entering from the outside and tending to flow along the terminal 19. To this end, I 95 provide a well or hopper 24 in which is placed a mass 25 of granular carbonaceous material which may be tightly tamped in place around the electrode. This means is fully described and claimed in a copending 100 application, and its action is not, therefore, further described here.

Each of the members 16 is in the form of a relatively shallow plate, preferably of a carbonaceous material, having a depression 26 in one surface and a corresponding projection 27 in the other surface thereof. The depression 26 provides a receptacle for

27
a mass 28 of granular carbonaceous resistor material which is placed therein. In order to build up the heating element it is only necessary to place a suitable number of members 16 on a table with the depression 26 facing upwardly, fill the depressions with granular carbonaceous material 28 to substantially the top surface of the plate. The members 16 may now be placed one above another, and, if slightly compressed, a projection 27 may be caused to interfit with a depression 26, compressing the material therein and also causing the adjacent members 16 to interlock with each other. The completed heating element may now be placed in its operative position in the furnace chamber substantially as illustrated in Figure 1, and compression may be employed to maintain the heating element in its operative position therein.

It may be noted that the use of the device embodying my invention provides a built-up resistor comprising solid and granular carbonaceous material, the built up resistor having a relatively high resistance. The device embodying my invention provides an interlocking resistor which, at the same time, provides means for preventing the oxidation of the granular material. It may be noted further that the resistor element is a relatively simple molded member and that the heating element may be easily built up whenever required.

Various modifications may be made in the device embodying my invention without departing from the spirit and scope thereof and I desire that only such limitations shall be placed thereon as are imposed by the prior art or are specifically set forth in the appended claims.

40 I claim as my invention:

1. In an electric furnace, the combination with a plurality of walls surrounding a furnace chamber, of a resistor in said chamber comprising a plurality of dished refractory electrical-conducting members, granular resistor material in each of said dished refractory members and resilient means for maintaining said dished members in interlocked position in said furnace chamber free of said walls.

2. An electric furnace resistor comprising a plurality of relatively shallow refractory electrical-conducting members, each member having a depression in one surface and a corresponding projection on the adjacent parallel surface, a quantity of granular electrical-resistor material in each of said depressions, and means for maintaining the projection of one member in operative position in the depression of an adjacent member.

55 In testimony whereof, I have hereunto subscribed my name this 26th day of May, 1921.

60 ORA A. COLBY.
